(57) **CLAIM**

The ornamental design for a controller adaptor, as shown and described.

DESCRIPTION

FIG. 1 is a front, top and right perspective view of a controller adaptor showing our new design;

FIG. 2 is a rear, bottom and left perspective view thereof;

FIG. 3 is a front view thereof;

FIG. 4 is a rear view thereof;

FIG. 5 is a right side view thereof, a left side view being a mirror image thereof;

FIG. 6 is a top plan view thereof;

FIG. 7 is a bottom plan view thereof;

FIG. 8 is a reference view thereof, shown in use with a controller attached; and,

FIG. 9 is a second reference view thereof.

The broken lines represent the portions of the design that form no part of the claim.
